SHOE SEWING MACHINE AND DRIVING AND
STOPPING MECHANISM THEREFOROtto R. Haas, North Beverly, Mass., assignor to
United Shoe Machinery Corporation, Flemington, N. J., a corporation of New JerseyOriginal application September 14, 1939, Serial
No. 294,926. Divided and this application October 23, 1941, Serial No. 416,228

22 Claims. (Cl. 112—219)

The present invention relates to shoe sewing machines and more particularly to driving and stopping mechanisms therefor.

In a shoe sewing machine, the operating parts are ordinarily of heavy construction and suitable treadle controlled driving and stopping mechanisms are provided to control the speed of operation and to bring the machine to rest with the stitch forming devices free of the work so that the work may readily be withdrawn at the end of the seam. In order to reduce the speed of the main sewing shaft of the machine and to rotate the shaft positively to a stopping position, it is usual to provide a low speed driving mechanism in addition to a high speed driving mechanism which is employed to drive the sewing shaft during sewing operations. Where the driving and stopping mechanism is controlled by a treadle actuated member, the high speed mechanism only is directly connected to the treadle member to be thrown into and out of operation thereby, the low speed mechanism being rendered operative automatically at a predetermined point in the rotation of the sewing shaft when the high speed mechanism is thrown out of operation. In use, there ordinarily is nothing to prevent the treadle controlled member from being actuated to throw out of operation the high speed driving mechanism at a position of the sewing shaft so close to the stopping point that the low speed driving mechanism either will not have an opportunity to act properly, thus causing a sudden impact in the machine, or a failure on the part of the stopping mechanism to bring the sewing shaft to rest in time. If careful adjustments are made in the driving and stopping mechanisms, these results may be obviated but such adjustments are difficult to effect, particularly where access is limited by the use of a completely enclosing casing structure on the machine.

In order to avoid the necessity of careful or frequent adjustments of the driving and stopping mechanism in the present sewing machine, means are provided for preventing the high speed driving mechanism from being thrown out of operation until the main shaft reaches substantially its normal stopping position, and preferably at all times during rotation of the main sewing shaft, except just before the position of the main sewing shaft is reached where the low speed driving mechanism ordinarily begins to drive the sewing shaft. The weight of the operating parts of the present machine has been substantially reduced through the use of modern materials and weight eliminating construction so that under certain circumstances, if the treadle controlled member is

5 moved to a stopping position while the stitch forming devices engage the work, the resistance offered by the work to the stitch forming devices may be sufficient to bring the machine to rest out of proper stopping position. Accordingly, in the present form of this feature of the invention, the means for preventing operation of the treadle member is effective until the stitch forming devices are free of the work. As hereinafter described, the treadle member is locked by a latch 10 in a position to cause the sewing shaft to be driven positively, and means actuated by the sewing shaft is provided to release the latch only while the stitch forming devices are disengaged 15 from the work. Thus the movements of parts will not be stopped by the resistance offered by the work before the stopping mechanism acts.

20 Other features of the invention include novel and improved constructions, arrangements, and combinations of parts, hereinafter described and claimed which, together with the advantages to be obtained thereby, will be readily understood by those skilled in the art from the following description taken in connection with the accompanying drawings.

25 In the drawings, Fig. 1 is a side view of a machine embodying the present invention, looking from the right of the machine, with the right end plate of the casing removed; Fig. 2 is a front view on an enlarged scale of the housing head of the machine, the casing being removed and end portions of the frame broken away; Fig. 3 is a plan view on a similar scale, with the casing shown in section; Fig. 4 is a sectional view of the sewing head with the right end plate removed; Fig. 5 is a right-hand side sectional view of the parts 30 at the front of the sewing head of the machine, as viewed along the line 5—5 of Fig. 3; Fig. 6 is a sectional view of the sewing head taken along the line 6—6 of Fig. 2; and Fig. 7 is a detail of 35 some of the parts indicated in Fig. 5, as viewed from the opposite side of the machine.

40 The illustrated machine is a lockstitch outsole shoe sewing machine of the same general construction and mode of operation as that disclosed in U. S. Letters Patents to French and Meyer, No. 473,870, of April 26, 1892, and is provided with stitch forming devices actuated by means of a single main sewing shaft rotated by a power driven belt engaging a pulley on the shaft. The machine is fully illustrated and described in applicant's United States Letters Patent No. 2,328,011, for Shoe sewing machines, granted August 31, 1943, on applicant's co-pending application Ser. No. 294,926, filed September 14, 1939, and of 45 which the present application is a division. The

main driving motor is indicated at 44 mounted on a support 46 secured to the machine frame. The driving pulley 50 of the motor is surrounded by a belt passing over a pulley 54 secured to a horizontal countershaft 56 mounted in bearings parallel to the sewing shaft 2 and provided with a pulley 60 engaged by a high speed driving belt 66 from which is driven a loose pulley 68 on the sewing shaft 2 forming the driving member for a high speed clutch. The countershaft 56 also carries a pulley which is engaged by a low speed driving belt 70 which passes over a driven pulley 74 carried by a worm shaft 76 engaging a worm wheel 78 loose on the main sewing shaft. The low speed stopping mechanism is similar to that disclosed in U. S. Letters Patent to Topham No. 1,099,328, dated June 9, 1914.

As has been stated, the high speed driving mechanism for the present machine is held from being thrown out of operation until the main sewing shaft 2 reaches substantially its normal stopping position. To engage the driving pulley 68 of the high speed driving clutch with the driven part of the clutch indicated at 142 in Fig. 2, the pulley 68 is acted upon by the upper forward end of a lever 144 fulcrumed on a pin 146 secured in the frame of the machine. The lower arm of the lever 144 is connected by a pair of toggle links 148 and 150 with the enlarged head of a bolt 152 slidably mounted within a lug portion of the machine frame. The central joint of the toggle links is connected to the upper end of a control rod 154, the lower end of which is connected to an arm 156 secured to a shaft 158 also carrying a foot treadle 160 extending forwardly of the machine through an opening in the cover structure. When the treadle rod 154 is depressed, the lever 144 moves the clutch members 68, 142 into engagement and at the same time the link 150 which is squared at one end moves beneath a latch lever 162 which locks the toggle links in substantial alignment until released. To cause the latch lever 162 to lock the link 150, the lever is connected by a spring 164 stretched between the lever and a pin on the machine frame and, when the machine is in stopped position, the lower end of the lever is held in inoperative position by the squared end of the link 150. By locking the toggle links 148, 150 in aligned position, the control rod 154 and treadle 160 are at the same time held depressed so that the sewing shaft is driven at high speed and the low speed stopping mechanism is held from operation until such time as the toggle link 150 is released by the latch lever. To release the link 150 from the latch lever 162, the upper end of the lever carries a roll 167 arranged to be engaged by a cam 166 on the driven clutch member 142. To render the action of the high speed clutch in starting the machine less abrupt and to prevent application of excessive pressures between the members of the clutch, the shank of the bolt 152 is surrounded by a spring 168 acting between the head of the bolt and an adjusting sleeve 170 threaded in the lug which supports the bolt.

The high speed driving mechanism of the present machine is held operative, and the low speed stopping mechanism is not operated to bring the sewing shaft to rest until after the needle and awl have become disengaged from the work in any sewing cycle. The resistance offered by the needle and awl while engaging or penetrating the work, particularly with thick work, is the greatest offered by any of the stitch forming devices during each sewing cycle and, since the resistance

may vary with different qualities of work if the high speed driving mechanism becomes inoperative during the engagement of the needle and awl with the work, the sewing shaft may come to rest at an irregular stopped position. To insure that the sewing shaft will be driven positively while the needle and awl are engaging the work, the link 150 and control rod 154 are not released by the latch lever 162 until after the needle and awl are disengaged and just before that part of the rotation of the sewing shaft where the low speed stopping mechanism becomes effective. The release of link 150 and control rod 154 occurs in the present machine directly after the middle of each sewing cycle, leaving approximately a half of the sewing cycle to slow down and bring the sewing shaft to rest.

As in the low speed stopping mechanism of the Topham patent above referred to, the machine is driven at low speed by a low speed driving clutch actuated by means of a vibrating lever having an opening which is engaged by a lock bolt after the operator removes his foot from the control treadle. In the present machine, the low speed driving clutch comprises the worm wheel 78, a driven clutch member 180 splined to a sleeve 182 secured to the sewing shaft 2 and forming a bearing for the worm wheel 78. The driven clutch member 180 is normally held out of engagement with the worm wheel by means of compression springs, one of which is indicated at 184 surrounding studs secured to lugs formed on the driven clutch member 180 and slideable in sleeves 186 mounted in similar lugs formed on sleeve 182. The hub of the driven clutch member has a cam groove 188 for actuating a vibrating lever 190 (see Fig. 3). During sewing operations, the driven clutch member 180 rotates with the sewing shaft and causes the lever 190 to oscillate once during each sewing cycle and, when the high speed driving clutch is thrown out of operation, the lock bolt, shown in Fig. 5 at 192, slides vertically in a carrier 194 into an opening in the vibrating lever 190 holding the lever stationary. The cam groove 188 is so shaped that during the continued rotation of the sewing shaft, the driven clutch member 180 engages the worm wheel 78 briefly to slow down the sewing shaft and thereafter moves away from the worm wheel to permit the sewing shaft to come to a uniform position of rest. When the machine is again started, the lock bolt is withdrawn from the vibrating lever by connections with the treadle 160 including a treadle rod 196, a pivoted cam arm 198 (see Fig. 7), and a cam follower lever 200 having a roll 204 and an arm connected by means of a link 206 with the lock bolt. When the latch lever 162 locks the high speed clutch in driving engagement, it also prevents movement of the treadle and of lock bolt against the vibrating lever 190, thus holding the low speed stopping mechanism from operation. The timed relation between the cam 166 of the high speed clutch and the cam slot 188 of the low speed stopping mechanism is such that the lock bolt may not engage the vibrating lever until after the opening in the lever is in alignment with the lock bolt and just before the active part of cam slot 188 is reached, the alignment of the lever with the lock bolt occurring only while the stitch forming devices engage the work and for a short interval thereafter. After the time in any sewing cycle when the lock bolt may engage the opening in the vibrating lever, the cam 166 allows the latch lever 162 to move under the influence of the spring 164 in a direction to lock the link 150 and the control rod

154 against upward movement so that if the low-speed driving mechanism has not been rendered operative by this time, it will again be held inoperative until the next sewing cycle.

The stitch forming devices of the machine include the curved hook needle and curved awl indicated at 208 and 210, respectively; an oscillating loop taker or shuttle 212 in which is rotatably mounted a thread case 214, main and auxiliary take-ups 216 and 218, a looper 220, a thread lifter 222, a thread clamp or lock lever 224, a tension 225, and other devices cooperating to form a lockstitch seam. The work is clamped in stationary relation to the stitch forming devices by a work support 226 and a presser foot 228 mounted on a presser foot lever 229, the work being fed while released from the clamping action of the presser foot by lateral movements of the awl, as in the machine of Patent No. 473,870. The stitch forming devices are actuated by suitable driving connections from the sewing shaft 2 to which there is secured a series of cams 230 shaped similar to the cams of the Patent No. 473,870 referred to, and composed of synthetic resinous material, as in present inventor's prior U. S. Letters Patent No. 2,037,722, of April 21, 1936. To assist further in bringing the machine to rest with the stitch forming devices uniformly in stopping positions, one of the cams 230 has a notch 232 along its periphery arranged to be engaged by a hook member 234 pivoted on a screw stud 236 threaded in the machine. During normal sewing operations, the hook member 234 is held free of the cam which has the notch 232, the hook member being brought yieldingly into engagement with the periphery of the cam just before the stopping position is reached.

The thread lock lever 224 is similar to that disclosed in Patent No. 473,870 and is actuated to clamp and release the needle thread as it passes over a thread guiding pulley 238 in timed relation to the motions of the other stitch forming devices. The lock lever is fulcrumed on a stud 240 and has one arm engaging a notch in the hub of an arm 242. Pivotedly connected with the arm 242 is one of a pair of toggle links 244 and 246, the other one of which is pivotally connected to a cam actuated lever 248 fulcrumed on the stud 236. During normal sewing operations, the toggle links 244 and 246 are held in alignment so as to transmit the motion of the cam lever to the thread lock. The movements of the cam lever 248 are such that when the sewing shaft passes through stopping position, the thread lock is closed. To permit needle thread to be drawn freely from the machine when in stopping position, normally inoperative mechanism actuated by the cam lever 248 is provided, which when rendered operative, breaks the alignment of the toggle links 244, 246.

The mechanism for breaking the alignment of the toggle links 244, 246 to release the thread from clamping engagement of the lock lever 224 also causes the hook member 234 to be moved yieldingly against the cam 230 and comprises a link 250 pivotally connected between the upper end of the cam lever 248 and an oscillating yoke 260, as best shown in Figs. 3 and 5. The yoke 260 is rotatably mounted on a rock shaft 262 supported in bearings 264 at the rear of the machine. During sewing operations, the yoke 260 is oscillated idly by the cam lever 248 and, when the latch lever 162 releases link 150 and the control rod 154, a latch arm 268 carried by one arm of a lever 270 swings into the path of move-

ment of an arm on the oscillating yoke 260, causing the lever 270 to be actuated. When the lever 270 is moved, connections including a link 272 connected to the lever 270 and a lever 274 fulcrumed on a fixed stud screw 276 cause the alignment of the toggle links 244 and 246 to be broken so that the thread lock 224 is held open. The lever 274 is also connected with the hook member 234 through a link 278 by means of a pin 280 which passes through the central joint of the toggle links, a horizontal slot in one arm of the lever 274 and the link 278. A vertically slotted connection is provided between the link 278 and the hook member 234 so that if the connections 10 thus described are actuated before the notch 232 on the cam 230 reaches a position opposite the hooked end of the hook member, no damage will result, the hook member being yieldingly urged against the periphery of the cam by a spring 282 stretched between an arm of the hook member and a stationary guide of the machine. The connections for unlocking and raising the presser foot from the work at the end of a seam include the rock shaft 262 on which is secured the lever 270, an arm 284 (see Figs. 4 and 6) loose on the rock shaft 262, a link 286 pivotally connected at its rearward end with the arm 284 and sliding loosely at its forward end in a perforated plate portion of a presser foot unlocking lever 288. The unlocking lever 288 is loosely mounted on the presser foot fulcrum pin 290, and is engaged by a check nut 287 on the rod 286 to release a pair of locking pawls 292 and 294 of the presser foot actuating mechanism in a manner similar to that disclosed in the U. S. Letters Patent to Topham, No. 1,289,312, of December 31, 1918. Upon continued movement of the rock shaft 262, a slotted arm 296 loose on the shaft 262 is engaged within its slot by a pin 297 on a lever 298 fast to the shaft, the slotted lever 296 having connected to it a link 300 and a lever 302. The lever 302 is mounted on a fixed pivot 304 and overlies at its forward end the upper portion of a harp-shaped frame 306 (Fig. 6) 35 similar to that described in Patent No. 473,870, which frame, as explained in said patent, is directly connected with the presser foot. Through the connections thus described, the presser foot is raised from the work after being unlocked. 40 To prevent continued movement of the presser foot unlocking connections after being actuated to unlock the presser foot, the arm 284 is operated by the lever 298 through a ball lock connection. The arm 284 rides between a plate-like 45 arm of the lever 298 and a fixed plate 308 secured to the bearing 264. A recess is provided in the plate-like arm of the lever 298 to receive a ball 310 sliding loosely through an opening in the arm 284, the plate 308 holding the ball partially within the recess of the lever 298 during 50 sewing operations and, when the rock shaft is actuated, the arm 284 moves with the lever until the ball 310 lines up with a recess 312 (see Fig. 3) in the plate 308. The ball 310 then slides out of the recess in the lever 298 and into the recess 312, locking the arm 284 to the plate 308 during 55 continued movement of the lever 298. 60 To actuate the latch member 268 towards and from latching relation with the arm of the oscillating yoke 260, the latch member is secured to one end of a pivot pin 314 loosely mounted in an arm of the sleeve 270. The other end of the pivot pin 314 carries an arm 316 having a stud 318 between which and a pin 320 on the lever 270 65 there is stretched a spring 322 tending to hold 70 75

the latch member in latching position. When the treadle rod is depressed to start the machine, the latch member 268 is moved to inoperative position by an S-shaped arm 324 (see Fig. 7) pivoted concentrically with the cam arm 198 and connected thereto through a pin and slot connection. The free end of the arm 324 overlies the pin 318 so that when the arm 324 is moved downwardly as the treadle rod is depressed, the latch member 268 is rocked out of engagement with the arm of the yoke 260. As soon as the latch member is rendered inoperative, a tension spring 326 connected between an arm 328 secured to the shaft 262 and a fixed part of the frame rocks the shaft 262 to cause the presser foot and stitch forming devices to operate in the usual way.

In order to stop the machine with the last loop of needle thread partially projecting from the upper surfaces of the work so that both threads may be severed close to the upper surface of the work by a single stroke of a hand knife, the driving and stopping mechanism including the cam having the notch 232 and the hook member 234 is so arranged that the machine will come to rest before the awl enters the work for a new stitch and after the needle loop pulls the loop of needle thread from the loop taker almost to the surface of the work. The stitch setting movement of the take-up occurs after the high speed driving mechanism has been rendered inoperative and while the sewing shaft is being driven at low speed. Also during this time, the presser foot is being lifted by the normally inoperative mechanism so that the power absorbed by these operations is provided by the low speed mechanism.

The nature and scope of the invention having been indicated and a particular embodiment of the invention having been described, what is claimed is:

1. A driving and stopping mechanism having, in combination, a main shaft, high and low speed mechanisms for driving said shaft, a treadle actuated control member for throwing the high speed driving mechanism into and out of operation, normally inoperative means rendered operative when the high speed mechanism is thrown out of operation to cause the low speed mechanism to drive said shaft through a predetermined part of a rotation and then to cause the shaft to come to rest, and means acting during each rotation of the main shaft to prevent the high speed driving mechanism from being thrown out of operation except when the main shaft is in substantially normal stopping position.

2. A driving and stopping mechanism having, in combination, a main shaft, high and low speed driving mechanisms for driving said shaft, a treadle actuated control member for rendering the high speed driving mechanism operative or inoperative, normally inoperative means driven by the main shaft for causing the low speed mechanism to drive the shaft through a predetermined movement and then to permit said shaft to come to rest when the high speed mechanism is thrown out of operation, and means for locking the control member from actuation except just before that part of a rotation of the main shaft where the low speed mechanism is caused to drive the main shaft.

3. A driving and stopping mechanism having, in combination, a main shaft, driving and stopping mechanisms including a vibrating lever actuated by the shaft, a lock bolt for engaging the

lever to bring the shaft to rest in a predetermined position, a treadle actuated control member for withdrawing the lock bolt from the vibrating lever and for throwing the driving mechanism into operation when moved in one direction and for releasing the lock bolt to cause its engagement with the vibrating lever when moved in the other direction, and means acting during each rotation of the main shaft to lock the treadle except during that part of the rotation of the shaft where the vibrating lever is in position to be engaged with the lock bolt.

4. A driving and stopping mechanism having, in combination, a main shaft, a vibrating lever having an opening actuated by the shaft, a lock bolt for engaging the lever to bring the shaft to rest in a predetermined position, a treadle actuated control member for withdrawing the lock bolt from the vibrating lever and for throwing the driving mechanism into operation when moved in one direction and for releasing the lock bolt to cause its engagement with the vibrating lever when moved in the other direction, a latch for locking the treadle against movement in a direction to cause the lock bolt to engage the lever, and means for releasing the latch from the treadle member when the vibrating lever is in a position to be engaged by the lock bolt.

5. A driving and stopping mechanism having, in combination, a main shaft, a vibrating lever having an opening actuated by the shaft, a lock bolt for engaging the opening in the lever to bring the shaft to rest in a predetermined position, a treadle actuated control member for withdrawing the lock bolt from the vibrating lever and for throwing the driving mechanism into operation when moved in one direction and for releasing the lock bolt to cause its engagement with the vibrating lever when moved in the other direction, a latch for locking the treadle against movement in a direction to cause the lock bolt to engage the lever, and a cam driven from the main shaft for actuating the latch to release the treadle member when the opening in the vibrating lever is in a position to receive the lock bolt.

6. A shoe sewing machine having, in combination, a main sewing shaft, stitch forming devices actuated thereby, driving and stopping mechanism for bringing said shaft to rest at the end of a seam, a treadle actuated control member for the driving and stopping mechanism arranged when actuated in one direction to cause the shaft to be driven and in the other direction to cause the shaft to be brought to rest, and means acting during each rotation of the main shaft to prevent movement of the treadle control member in a direction to cause the shaft to be brought to rest in any sewing cycle until after the stitch forming devices are free of the work.

7. A shoe sewing machine having, in combination, a main sewing shaft, stitch forming devices actuated thereby, driving and stopping mechanism for bringing said shaft to rest at the end of a seam, a treadle actuated control member for the driving and stopping mechanism arranged when actuated in one direction to cause the shaft to be driven and in the other direction to cause the shaft to be brought to rest, and means acting during each rotation of the main shaft to lock the treadle control member during each sewing cycle in a position to cause the sewing shaft to be driven until the stitch forming devices are free of the work.

8. A shoe sewing machine having, in combination, a main sewing shaft, stitch forming de-

vices including a needle actuated thereby, driving and stopping mechanism for bringing said shaft to rest at the end of a seam with the stitch forming devices free of the work, a treadle actuated control member for the driving and stopping mechanism arranged when actuated in one direction to cause the shaft to be driven and in the other direction to cause the shaft to be brought to rest, a latch for locking the treadle member in a position to cause the sewing shaft to be driven, and means actuated by the sewing shaft to release the latch from the treadle member during each sewing cycle while the needle is disengaged from the work.

9. A shoe sewing machine having, in combination, a main sewing shaft, stitch forming devices actuated thereby including a needle and an awl, a driving and stopping mechanism having high and low speed mechanisms for driving the sewing shaft, a treadle actuated control member for rendering the high speed driving mechanism operative or inoperative, and normally inoperative means acting when the high speed mechanism is thrown out of operation and only during that part of a sewing cycle where the needle and awl are disengaged from the work to cause the low speed driving mechanism to drive said shaft through a predetermined movement and then to permit the shaft to come to rest.

10. A shoe sewing machine having, in combination, a main sewing shaft, stitch forming devices actuated thereby including a needle and an awl, a driving and stopping mechanism having high and low speed mechanisms for driving the sewing shaft, a treadle actuated control member for rendering the high speed driving mechanism operative or inoperative, normal inoperative means driven by the sewing shaft for causing the low speed mechanism to drive said shaft when the high speed mechanism is thrown out of operation and after the needle disengages the work, and then to permit the shaft to come to rest before the awl enters the work, and means for preventing the high speed mechanism from being rendered inoperative in each sewing cycle until after the needle is disengaged from the work.

11. A shoe sewing machine having, in combination, a main sewing shaft, stitch forming devices actuated thereby including a needle, an awl, a loop taker and a take-up for pulling each loop of needle thread from the loop taker and for setting the stitches, driving and stopping mechanism having high and low speed mechanisms for driving the sewing shaft, a treadle actuated control member for rendering the high speed driving mechanism operative or inoperative, and normally inoperative means acting when the high speed mechanism is thrown out of operation and before the awl enters the work to cause the low speed mechanism to drive said shaft and then to permit the shaft to come to rest after the take-up pulls the needle loop from the loop taker and before the take-up acts to set the final stitch of a seam.

12. A shoe sewing machine having, in combination, a main sewing shaft, stitch forming devices actuated thereby including a needle, an awl, a loop taker and a take-up for pulling each loop of needle thread from the loop taker and for setting the stitches, driving and stopping mechanism having high and low speed mechanisms for driving the sewing shaft, a treadle actuated control member for rendering the high speed driving mechanism operative or inoperative, normally

inoperative means acting when the high speed mechanism is thrown out of operation and before the awl enters the work to cause the low speed mechanism to drive said shaft and then to permit the shaft to come to rest after the take-up pulls the needle loop from the loop taker and before the take-up acts to set the final stitch of a seam, and means for preventing the high speed driving mechanism from being rendered inoperative in each sewing cycle until the needle is disengaged from the work and before the take-up pulls the needle loop from the loop taker.

13. A shoe sewing machine having, in combination, a main sewing shaft, stitch forming devices actuated thereby including a needle, an awl, a loop taker and a take-up for pulling each loop of needle thread from the loop taker and for setting the stitches, driving and stopping mechanism having high and low speed mechanisms for driving the sewing shaft, a treadle actuated control member for rendering the high speed driving mechanism operative or inoperative, normally inoperative means acting when the high speed mechanism is thrown out of operation and before the awl enters the work to cause the low speed mechanism to drive said shaft and then to permit the shaft to come to rest after the take-up pulls the needle loop from the loop taker and before the take-up acts to set the final stitch of a seam, a latch for holding the treadle member in a position where the high speed driving mechanism is operative, and a cam on the sewing shaft for releasing the latch from the control member in each sewing cycle while the needle is being disengaged from the work.

14. A shoe sewing machine having, in combination, a main sewing shaft, stitch forming devices actuated thereby, and driving mechanism for the sewing shaft including a driving clutch member, a driven clutch member, a pair of toggle links arranged at one end to press the clutch members together, a treadle connected to the middle joint of the pair and a spring connected at the other end of said pair of toggle links to prevent the exertion of excess pressures of the links on the clutch members.

15. A sewing machine having, in combination, a main sewing shaft, stitch forming devices, driving and stopping mechanism having a vibrating lever and a lock bolt for engaging the vibrating lever to bring the sewing shaft to rest at the end of a seam with the stitch forming devices free of the work, a treadle actuated control member for withdrawing the lock bolt from the vibrating lever and for causing the sewing shaft to be started when actuated in one direction and for releasing the lock bolt to permit its engagement with the vibrating lever when actuated in the other direction, the vibrating lever being held in alignment to receive the lock bolt while the stitch forming devices engage the work and for a short interval thereafter, and means acting during each rotation of the main shaft to prevent the lock bolt from engaging the vibrating lever while the stitch forming devices engage the work.

16. A sewing machine having, in combination, a main sewing shaft, stitch forming devices, driving and stopping mechanism having a vibrating lever and a lock bolt for engaging the vibrating lever to bring the sewing shaft to rest at the end of a seam with the stitch forming devices free of the work, a treadle actuated control member for withdrawing the lock bolt from the vibrating lever and for causing the sewing shaft to be started when actuated in one direction and for releasing

the lock bolt to permit its engagement with the vibrating lever when actuated in the other direction, the vibrating lever being held in alignment to receive the lock bolt while the stitch forming devices engage the work and for a short interval thereafter, a latch for locking the treadle actuated member from movement in a direction to release the lock bolt, and a cam on the sewing shaft for releasing the latch for a short interval only while the stitch forming devices are free of the work.

17. A sewing machine having, in combination, a main sewing shaft, stitch forming devices actuated thereby, a presser foot, a driving and stopping mechanism for the sewing shaft having high and low speed mechanisms for driving the sewing shaft, a treadle actuated control member for throwing the high speed mechanism into and out of operation, normally inoperative means rendered operative when the high speed mechanism is thrown out of operation to cause the low speed mechanism to drive said shaft through a predetermined part of a rotation and to bring the sewing shaft to rest at the end of a seam with the stitch forming devices free of the work, an oscillating part actuated by the sewing shaft, a latch for connecting the oscillating part and the presser foot when the driving and stopping mechanism is thrown into operation to lift the presser foot as the sewing shaft comes to rest, and means connected to the treadle actuated member for holding the latch out of latching position during sewing operations.

18. A sewing machine having, in combination, a main sewing shaft, stitch forming devices actuated thereby, a presser foot, a driving and stopping mechanism for the sewing shaft having high and low speed mechanisms, a treadle actuated control member for throwing the high speed mechanism into and out of operation, normally inoperative means rendered operative when the high speed mechanism is thrown out of operation to cause the low speed mechanism to drive the sewing shaft and to bring the shaft to rest at the end of a seam with the stitch forming devices free of the work, an oscillating part actuated continuously by the sewing shaft, and a latch for connecting the oscillating part and the presser foot when the low speed mechanism is thrown into operation to lift the presser foot as the sewing shaft comes to rest.

19. A sewing machine having, in combination, a main sewing shaft, stitch forming devices including a sewing thread lock, a presser foot, a lever oscillated by the sewing shaft to open and close the thread lock during each sewing cycle, driving and stopping mechanism having a vibrating lever and a lock bolt received by the lever to bring the sewing shaft to rest at the end of a seam with the stitch forming devices free of the work, a treadle actuated control member for withdrawing the lock bolt from the vibrating lever and for causing the sewing shaft to be driven when actuated in one direction, and

for releasing the lock bolt to cause its engagement with the vibrating lever when actuated in the other direction, means actuated by the thread lock lever arranged when the treadle actuated member releases the lock bolt to prevent the thread lock from closing during the final movement of the sewing shaft, and means for locking the treadle member from movement out of a driving position, except during that part of a rotation of the sewing shaft when the vibrating lever is in position to receive the lock bolt.

20. A sewing machine having, in combination, a main sewing shaft, stitch forming devices including a sewing thread lock, a lever oscillated by the sewing shaft to open and close the thread lock during each sewing cycle, driving and stopping mechanism, a treadle actuated control member for causing the sewing shaft to be started and for rendering the driving and stopping mechanism operative to bring the sewing shaft to rest at the end of a seam with the stitch forming devices free of the work and with the thread lock lever in a thread locking position, and means actuated by the thread lock lever arranged when the driving and stopping mechanism is thrown into operation to prevent the thread lock from locking the thread during the final movements of the sewing shaft.

21. A shoe sewing machine having, in combination, a main sewing shaft, stitch forming devices including a thread lock, a lever oscillated by the sewing shaft, a toggle connected between the thread lock and the lever to cause the thread lock to be closed and opened during each sewing cycle, driving and stopping mechanism, a treadle actuated control member for causing the sewing shaft to be started and for throwing the driving and stopping mechanism into operation to bring the sewing shaft to rest at the end of a seam with the stitch forming devices free of the work, and means under the control of the treadle member for breaking the toggle before the sewing shaft is brought to rest to prevent the thread lock from being closed during the last sewing cycle.

22. A shoe sewing machine having, in combination, a main sewing shaft, stitch forming devices including a thread lock, a lever oscillated by the sewing shaft, a toggle connected between the thread lock and the lever to cause the thread lock to be closed and opened during each sewing cycle, driving and stopping mechanism, a treadle actuated control member for causing the sewing shaft to be started and for throwing the driving and stopping mechanism into operation to bring the sewing shaft to rest at the end of a seam with the stitch forming devices free of the work, and connections between the thread lock lever and the toggle comprising a latch controlled by the treadle member for breaking the toggle before the sewing shaft is brought to rest to prevent the thread lock from being closed during the last sewing cycle.
